CLAIM

The ornamental design for a combined mallet and pin remover, as shown and described.

DESCRIPTION

FIG. 1 shows a top view of the design;

FIG. 2 shows a side view of the design;

FIG. 3 shows a further side view of the design rotated 90° from the view of FIG. 2;

FIG. 4 shows a further side view of the design rotated 90° from the view of FIG. 3 and rotated 180° from the view of FIG. 2; and,

FIG. 5 shows a bottom view of the design.

FIG. 1

FIG. 2

FIG. 4

FIG. 3

FIG. 5
